UNITED STATES PATENT OFFICE.

JOHN KLEPACH, OF CEDAR RAPIDS, IOWA.

GRAVEL CLEANER.

Application filed December 7, 1922. Serial No. 605,499.

To all whom it may concern:

Be it known that I, JOHN KLEPACH, a citizen of the United States, residing at Cedar Rapids, in the county of Linn and State of Iowa, have invented certain new and useful Improvements in Gravel Cleaners; and I do hereby declare the following to be a full, clear, and exact description of the invention, such as will enable others skilled in the art to which it appertains to make and use the same.

This invention relates to the preparation of gravel as pumped from watercourses so as to render the same fit for use in the making of concrete, and analogous building operations.

The object of the invention is to provide apparatus whereby the refuse matter found in river gravel, such as mud, waterlogged sticks, bark, leaves, etc., may be easily and cheaply separated from the gravel, so as to leave the latter in a suitable condition for concrete mixtures, and the like.

The invention represents an improvement in apparatus for the purpose as illustrated and described in a companion application for patent, No. 605,498 filed December 7, 1922. In said application a single sluice-box is shown and described, while in this application a pair of such sluice-boxes are set side-by-side, and provision is made for alternately dumping them and at the same time shunting the flow of material to the other sluice-box, whereby the separating operation is made continuous.

The invention is fully described and claimed herein, reference being had to the accompanying drawing, in which:—

Fig. 1 is a side elevation of my improved gravel cleaner. Fig. 2 is a central, longitudinal section of the same. Fig. 3 is a plan view of the same. Fig. 4 is a cross section on the line 4—4 of Fig. 3, looking to the right.

On suitable supports 5 is mounted a long sluice-box 6, separated into two adjoining compartments by a longitudinal partition 7. Each of these compartments is provided with a dropping bottom-board 8, herein shown hinged at the inner sides to the mid-rib 7^a, to which the partition is preferably attached by brace-irons 9. The bottom-boards are provided with lateral arms 8^a, which connect by short chains 10 with a longer, horizontal chain 11, at each side of the sluice-box. The chains are supported

by sheaves 12, and to each long chain is attached a heavy weight 13 to counterbalance the weight of the gravel as accumulated on the bottom-board. When the weight of the load exceeds that of the counterweight, the bottom-board swings downwardly, dumping the load, as shown in Fig. 4. A shallow cavity is formed for the gravel, by a baffle-board 14 at the lower end of the bottom-board, (as respects the flow of material), and thick cross-planking 15 at the upper end.

Referring to Figs. 2 and 3 it will be seen that the partition extends about as far toward the head end of the sluice-box as the bottom-boards. Directly opposite this end of the partition is the mouth of a pipe or trough 16, which is supposed to communicate with a sand-pump (not shown), which supplies the gravel mixed with a large proportion of water, from the river bed. The course of the material as discharged from the pipe is controlled by a deflecting board 17 hinged at 18 to the end of the partition. This deflecting guide-board is controlled by chains 19 passing over sheaves 20, and connecting with the respective bottom-boards. It will be evident that when one of the bottom-boards descends with its load of gravel, the guide-board will be drawn toward it. This deflects the current of flowing material into the other compartment, whose bottom-board is already up and ready to receive it. This action being alternative, there is no pause in the action of the apparatus due to the dumping of the load, and its operation is thus continuous.

To rid the bottom-boards of any adhering material after dumping, the apparatus is provided with a shaker, the same being a hand-lever 21 each side of the sluice-box, and connecting with the suspending chain. By this means the bottom-boards may be shaken to dislodge any sticking material.

I claim:

1. In a gravel-cleaner, a long sluice-box to receive the material, a longitudinal dividing partition, laterally hinged bottom-boards for each compartment, load-suspending means connecting with said bottom-boards, a deflecting board at the receiving end of the sluice-box, to shunt the material to either compartment, and means adapted to deliver the material in a watery, flowing condition to said sluice-box.

2. In a gravel-cleaner, a long sluice-box

to receive the material, a longitudinal dividing partition, an adjustable deflecting-board at the receiving end thereof, hinged bottom boards for each compartment, means 5 for supporting a load thereon, means for delivering the flowing material to the sluice-box, and means connecting the deflecting board with the respective bottom-boards, whereby the material is shunted from the compartment being emptied to the other.

3. In a gravel-cleaner, a long sluice-box to receive the material, a longitudinal dividing partition, a deflecting-board hinged at its upper end, separate bottom-boards 15 hinged to the bottom of the partition, means for supporting a load thereon by gravity, chains connecting the deflecting-board with the respective bottom-boards, supporting sheaves therefor, and means adapted to deliver the material in a watery, flowing condition to the receiving end of the sluice-box.

4. In a gravel-cleaner, a long sluice-box to receive the material, a deflecting-board hinged to its upper, receiving end, bottom-boards hinged to the bottom of the parti- 20

tion, and below the receiving and discharging level of material in the box, means adapted to connect the bottom-boards with the deflecting board, and thereby shunt the flowing material to the bottom-closed compartment, and means for supplying the watery, flowing material to the sluice-box.

5. In a gravel-cleaner, a long sluice-box to receive the material, a longitudinal dividing partition therefor, a laterally swingable deflecting-board hinged to the receiving end of the partition, a material-supplying pipe in substantially central alignment with the partition, laterally hinged bottom-boards for each compartment, and means connecting 35 each bottom-board with the deflecting-board, whereby the inflowing material is shunted from the dumping compartment to the other.

In testimony whereof I affix my signature in presence of two witnesses.

JOHN KLEPACH.
